FILTER

Peter Beghetti, San Francisco, Calif.

Application January 11, 1936, Serial No. 58,688

4 Claims. (Cl. 210—85)

This invention relates to filters as used principally for household purposes by attachment to the kitchen faucet, and has for its object an improved construction provided with means for separating impurities from the water, and means for collecting the impurities at a point out of the main stream of water and away from the filtering surface. Also my improved construction provides for rapid and thorough flushing of the device including the filtering surface by the main stream of water coming through the faucet without removal of the device from the faucet. Other advantages will appear in the following description and accompanying drawing.

15 In the drawing Fig. 1 is a vertical section of my filter as applied to a faucet.

Fig. 2 is a sectional view of the device as seen from line 2—2 of Fig. 1, the main filter device appearing in plan beyond the section line.

20 In detail, the filter comprises a vertically disposed hollow main cylindrical body 1, having a base cap 2 of generally conical form screwed over the lower open end of the body at 3, the apex of the cap being lowermost, and a vertically directed interiorly threaded opening 4 is provided through the apex of the cap which opening is fitted with a threaded plug 5.

The cylindrical body is divided by a horizontal partition 6 about midway of its upper and lower ends which partition is formed on its underside with an annular shoulder or ledge 7 against which is sealed one or more filter screens or cloths 8 in the shape of circular disks, which disks held in place by a coil spring 9 engaging around the periphery of the disks and between the disks and inwardly projecting ledge 10 formed around the upper or base end of conical cap 2. A light sheet metal cone 11 is positioned within the cap 2 with its conical end in vertical alignment with the opening 4, and having a flange 12 at its base end interposed between the lower end of the coil spring and ledge 10, said cone 11 being of greater angularity than cap 2 thereby providing a space 13 between the outer side of the cone 11 and undersides of cap 2 to form a dirt trap, a small opening 14 being provided at the apex of cone 11 to permit impurities in the water to pass into said space 13 from the enlarged space 15 between the cap 2 and partition 6.

50 Above the partition 6 there is a vertically extending cylindrical chamber 16 opening outwardly at the upper end of body 1 and interiorly machined to provide a close bearing surface for a cylindrical plug 17 that extends about to the upper end of the body 1, the upper end of the plug

17 being turned down to provide a cylindrical extension 18 of smaller diameter than plug 17 which extension extends outwardly of the body and is threaded at its upper end to attach a pipe fitting 19 that is interiorly threaded at its upper end for securing rigidly to the threaded end of a faucet 20.

An upper cap 21 is screwed over the upper open end of body 1, which cap carries a packing nut and packing 22 embracing the extension 18 to form a liquid seal around the extension at the upper end of body 1. A coil spring 23 is interposed between the upper end of plug 17 and the cap 21 and disks 24 of light resilient sheet metal are interposed between the lower end of plug 17 and the upper side of partition 6 to insure a tight seal.

The plug 17 and extension 18 may be cast with a central vertical bore 25 that extends laterally at a point just above the bottom of plug 17 as at 26 to the outside of the plug, or the plug and extension may be drilled out of a cylindrical bar formed to the desired shape.

At one side of the body 1, a duct 28 communicates between the upper chamber 16 at its upper end at the level of the lateral outlet 26, and at its lower end duct 28 communicates with the upper end of space or chamber 15 below the partition 6 and filter screens 8.

On the side of chamber 16 opposite the upper end of duct 28 is an opening 29 that communicates with the inner end of a bore 30 through a laterally and downwardly projecting spout 31. The inner end of bore 30 also communicates with an opening 32 communicating between space 33, 35 that is, above filter screens 8 and below partition 6.

In operation, the filter body is rotatable on plug 17 and extension 18, and normally is positioned so that the water from the faucet will pass through bore 25, 26, duct 28, space 15, opening 32 and out through bore 30. The flow is therefore upwardly through screens 8 and any impurities stopped by screens 8 will settle through space 15 and through opening 14 in cone 11 to be trapped in space 13 between the cap 2 and cone 11 from which trap they can readily be drained through opening 4 after removal of plug 5.

However, some of the finer impurities will tend to stick in screen 8, and these are quickly removed by merely rotating the body 1 so that port or outlet 26 will register over opening 29, and in this position the operator may merely place his finger over the outlet of spout 30 and turn on the faucet, thus reversing the flow of water 55

through screens 8 and cleansing the screens, the plug 5 being removed, such impurities as well as any collecting in spaces 15 and 13 will be flushed out through opening 4.

5 If desired a gate 35 may be provided on the outlet end of spout 31 to close the outlet, instead of the operation using his finger. In the drawing, such gate is indicated as having arms 36, pivoted at 37 to the sides of the spout and the 10 gate is resiliently held against the end of the spout by a coil spring 38, a square guide post 39 on the gate slidably extending through cross-bar 40 connecting the ends of the arms behind the gate.

15 After cleansing the filter screen as described, the body 1 can then be turned back to the position indicated in the drawing.

Replacement of screens 8 is readily accomplished by removing cap 2 and spring 9 and merely inserting the new screens and replacing the 20 cap and screen.

Having described my invention, I claim:

1. A filter of the character described comprising a hollow body having an upper and a lower 25 chamber therein and a partition between said chambers, a nozzle at one side of the body arranged with its bore communicating at its inner end with the upper and lower chamber, a duct communicating between the upper and lower 30 chamber at its opposite ends respectively and a plug rotatably fitted in said upper chamber having a bore therethrough one end of said bore in the plug registering over the end of said duct communicating with the upper chamber and the 35 bore of the plug being adapted to communicate with the bore of the nozzle when the body is rotated relative to said plug, a filter screen extend-

ing over the end of that portion of the bore of the nozzle that communicates with the lower chamber, said lower chamber being provided with an opening at its lower end and a removable plug fitted in said opening.

5

2. In a construction as defined in claim 1, said rotatable plug in the upper chamber being provided with a vertical extension having a bore therethrough in extension of the bore through the plug and means at the upper end of said vertical 10 extension for securing to the outlet of a faucet.

3. A filter of the character described comprising a hollow body having a partition therein dividing the body into an upper and a lower chamber, said upper chamber being provided with a 15 pair of spaced outlets in its side walls, a valve member rotatably fitted within said upper chamber and against said partition, said member having an inlet and an outlet, the outlet being positioned to selectively register with the spaced outlets in the side of the chamber upon rotating the member and body relatively. A filter screen fitted across said lower chamber, a duct communicating between one of said outlets and the portion of the lower chamber on one side of said 20 screen and a duct communicating between the other of the outlets and the portion of the lower chamber on the opposite side of said screen, and a discharge nozzle arranged with its bore communicating with said last mentioned duct.

25

4. In a construction as defined in claim 3, means for closing the bore of the nozzle to flow of fluid therethrough and means on said valve member for securing the same to a faucet with its inlet over the discharge end thereof.

30

PETER BEGHETTI.
